UNITED STATES PATENT OFFICE.

CLARENCE E. RAMSAY, OF PALMER, OREGON.

SPARK ARRESTER.

Application filed May 16, 1921. Serial No. 469,914.

To all whom it may concern:

Be it known that I, CLARENCE E. RAMSAY, a citizen of the United States, residing at Palmer, in the county of Multnomah and 5 State of Oregon, have invented a new and useful Spark Arrester, of which the following is a specification.

This invention relates to spark arresters especially designed for use on wood burning 10 locomotives although it is to be understood that the same can be applied to any locomotive stack if there is danger of sparks issuing from the stack and setting fire to property in the vicinity of the locomotive.

15 It is an object of the invention to provide a spark arrester utilizing a foraminous spark deflecting cone constituting the top closure for a spark retaining compartment mounted on the stack, means being provided 20 whereby this cone can be raised or lowered relative to the wall of the compartment so as to allow the products of combustion to pass freely from the stack under certain conditions, as while the fire is being started 25 in the locomotive.

A further object is to provide the cone with an annular deflecting means whereby 30 sparks issuing from under the raised cone will be deflected downwardly close to the locomotive.

With the foregoing and other objects in view which will appear as the description 35 proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

40 In the accompanying drawings the preferred form of the invention has been shown.

In said drawings—

Figure 1 is a vertical section through the 45 upper portion of a locomotive stack and showing the present improvements combined therewith.

Figure 2 is a section on line 2—2, Figure 1.

Referring to the figures by characters of 50 reference 1 designates the inverted frusto-conical bottom of the spark arrester, the same being provided with a depending annular flange 2 adapted to fit closely around the stack S of a locomotive and to be 55 clamped thereto by a split ring 3 extending around the flange. Spark conducting

tubes 4 extend downwardly from the lower portion of this frusto-conical bottom 1 and are adapted to convey from the device those sparks accumulating on the bottom 1. 60

An annular flange 5 is formed upon the upper portion of the bottom 1 and fulcrumed or otherwise secured thereto is a ring 6 angular in cross section and which extends around and is secured to the lower 65 portion of a cylindrical screen 7. The upper portion of this screen extends into and is secured to a ring 8 angular in cross section and adapted to support another ring 9 which is secured to and extends around the 70 upper portion of a conical screen 10. This screen projects downwardly into the cylindrical screen 7 and is provided, at its upper or large end with an outwardly and downwardly curved flange 11 extending beyond 75 the screen 7. The middle portion or apex of the screen 10 has a screw 12 swiveled therein, there being a head 13 on the upper portion of this screw and above the apex portion of the screen 10 where it can be 80 conveniently reached by a suitable tool for the purpose of rotating the screw within the screen 10. The threaded portion of the screw 12 engages a spider 14 secured in the upper portion of the stack S, preferably in 85 the same plane with the ring 3.

When it is desired to have the draft through the stack practically unobstructed the ring 9 can be disconnected from the ring 8 and by rotating the screw 12 the cone 90 10 will be elevated so as thus to provide an annular space between the rings 8 and 9. Thus while a fire is being started in the locomotive the products of combustion will flow freely along the cone and out under 95 the projecting flange 11 which will tend to direct sparks and other hard products of combustion downwardly. After the fire has been properly started the screen 10 can be adjusted downwardly so as to cause the ring 100 9 to contact with the ring 8 after which the parts can be fastened together if so desired by means of the bolts shown in Figure 1.

A damper 15 can be mounted in the stack S for controlling the draft. 105

What is claimed is:—

A spark arrester of the class described comprising an inverted hollow truncated cone having an outstanding flange at its upper end, a cylindrical screen disposed above 110 said flange and having an annular ring secured to its lower end, said ring being

angular in cross section with one flange resting on and secured to the flange of said cone, a similar ring secured to the upper end of said cylinder, a conical screen mounted in said cylinder and having an outwardly and downwardly curved flange to form an annular spark deflector, a ring secured to said conical screen and adapted to rest on and be detachably engaged with the ring at 10 the upper end of the cylinder, and means

for adjusting said conical screen relatively to said cylinder.

In testimony that I claim the foregoing as my own, I have hereto affixed my signature in the presence of two witnesses.

CLARENCE E. RAMSAY.
